TELEVISION SCANNING APPARATUS

Jan van der Mark, Eindhoven, Netherlands, assignor, by meane assignments, to Radio Corporation of America, New York, N. Y., a corporation of Delaware

Application June 21, 1939, Serial No. 280,283
In the Netherlands June 23, 1938

4 Claims. (Cl. 178—7.2)

This invention relates to a television transmitting device comprising an electron-image scanner. A known electron-image scanner comprises a screen sensitive to radiation, preferably sensitive to visible light, on which is projected the stationary or moving picture to be transmitted, and also means for obtaining a scanning beam, usually a beam of cathode rays, which is caused to travel over the screen by means of deflector coils or plates in such manner that the various points of the screen are successively scanned. Thus one obtains in an output circuit a current, the amplitude of which is varied as a function of the brightness of the picture points to be scanned.

It is found, however, that a picture scanned by such an electron scanner does not exactly correspond to the original picture after reproduction and, that particularly, shade formations occur which were not present in the original picture. One reason for this phenomenon lies in the fact that during scanning of the points of the screen secondary electrons and photo-electrons are dislodged which may return to other points of the screen and produce at these points potential variations. Owing to this, the potential at those points will no longer correspond to the brightness of the picture point there projected.

To avoid this undesirable phenomenon, according to this invention, means are provided, between the stationary or moving picture to be transmitted and the radiation-sensitive screen of the electron-image scanner, which ensure that at least part of the picture points adjacent each other in the direction of line scanning is projected in an exposed manner and another part is projected in an unexposed manner onto the screen such that exposed and unexposed parts of adjacent picture points adjoin each other. In addition, means are provided for deriving a current from the output currents obtained after exploration of the screen, the amplitude of this current being substantially dependent upon the difference between the successive amplitudes of the output currents brought about by scanning of successive exposed and non-exposed portions of the screen.

The invention will be more clearly understood with reference to the accompanying drawings in which:

Fig. 1 shows one embodiment thereof;
Figures 2 through 6 are explanatory curves;
Fig. 7 shows a lens raster construction.

The form of construction shown in Fig. 1 comprises an electron-image scanner 1 together with a photoelectric screen 2 on which the picture 3

is to be transmitted is projected by means of an optical system constituted by an objective 4, a field lens 5 and a second objective 7. Between the picture 3 to be transmitted and the screen 2, there is positioned behind the field lens 5 a line raster 6, whose lines are normal to the direction in which the lines of the picture projected onto the screen 2 are scanned.

Due to the presence of the raster 6, it is ensured that at least part of the points of the picture 3 adjacent each other in the direction of line scanning is projected in an exposed manner and part is projected in an unexposed manner onto the screen such that exposed and unexposed parts of adjacent picture points adjoin each other. By way of example, if the number of opaque lines of the line raster 6, if a picture has to be scanned according to 405-line definition and the ratio of the length of a picture line to the height of the image is 4/3, while only $\frac{4}{5}$ of the length of the picture lines is scanned (the remaining $\frac{1}{5}$ part is reserved for synchronization purposes) is in this case

$$\frac{4}{3} \cdot \frac{9}{10} \cdot 405 = 486$$

These opaque lines are separated by transparent lines of equal number and equal width.

The screen 2 of the electron scanner 1 on which the picture 3 to be transmitted is thus projected is constituted by a number of insulated photoelectric particles 8 applied on an insulating underlayer which is carried by a conductive area 10, to which is connected the output circuit of the electron image scanner.

The electron-image scanner comprises, in addition, a system of electrodes for producing an electron beam which is caused to traverse the screen 2 in two directions by means of deflector coils 11 and 12.

The loads of the photoelectric elements 8 obtained by means of the projection 1 of the picture 3 onto the screen 2 are compensated by means of the scanning beam with the result that a voltage is set up through a resistance 13 connected to the conductive area 10, the variation of this voltage as a function of time for the duration of a scanning line being schematically represented in Fig. 2. This figure shows the voltage e_p of the point P relatively to the point Q earthed, for example, and this voltage is negative.

Due to the scanning electron beam striking successively exposed and unexposed parts of the screen 2, the output current of the electron image scanner and consequently the voltage

through the resistance 13 is periodically interrupted with a frequency depending upon the speed at which the electron beam is moved across the screen 2 in the line direction and upon the number of unexposed lines per picture point, which number is determined by the raster 6. If, as is preferably done, each point of the screen 2 corresponding to a point of the picture 3 to be transmitted is constituted only by an exposed and an unexposed part, the frequency with which the voltage through the resistance 13 is periodically interrupted is double the highest picture current frequency determined by the number of picture points to be scanned per second.

When the scanning electron beam strikes an exposed element of the screen 2, the amplitude a_1 of the voltage through the resistance 13 is determined firstly by the brightness of the part of a picture point projected onto this element and, secondly, by the variation of potential which this element has obtained due to the secondary electrons and photo-electrons being dislodged during scanning from other elements of the screen, which electrons have returned to the screen and have in part gained access to the screen element in view.

When the scanning electron beam strikes the next non-exposed element of the screen 2 the amplitude a_2 of the voltage through the resistance 13 is exclusively determined by the variation of potential due to the secondary electrons and photo-electrons fallen on this unexposed element, since the number of secondary electrons striking adjacent exposed and unexposed elements of the screen 2 is approximately the same. The difference between the amplitudes a_1 and a_2 is merely dependent upon the brightness of the point of the picture 3 to be transmitted which corresponds to the exposed and unexposed element of the screen 2.

Consequently, a voltage must be derived from the voltage through the resistance 13, the amplitude of this voltage being determined by the difference between the successive amplitudes a_1 and a_2 .

This may be effected by supplying the voltage across the resistance 13 to a rectifier, for example a diode 17, through an amplifier 14 transmitting all frequency components of the said voltage, and through a condenser 15, which rectifier may be supplied with a bias, a leakage resistance 16 being provided between anode and cathode of the diode. The voltage e_R set up in the output circuit of the amplifier 14, i. e. the voltage of the point R relatively to the point S earthed, for example, is represented in Fig. 3. This voltage corresponds to the voltage of the point P relatively to Q, the amplification brought about by the amplifier 14 not being considered. The voltage of the point R relatively to S is positive because the voltage variations amplified by the amplifier 14 are superimposed on a constant D. C. voltage, viz. the D. C. anode voltage of the last amplifying tube of the amplifier 14. The polarity of the voltage e_R is such that during the occurrence every time of the amplitude a_2 in the voltage e_p through the resistance 13, the anode of the diode 17 is more positive than during the occurrence of the amplitude a_1 in the voltage e_p .

When the anode of the diode 17 is supplied with a positive voltage with respect to the cathode, a current flows in the diode charging the condenser 15. If the diode is dimensioned sufficiently large so that this is capable of supplying a high current at low anode voltages, the condenser 15

is charged upon the occurrence of the first impulse I_1 in the voltage e_p to a voltage equal to the amplitude e_{R_1} of this impulse. If, furthermore, the time constant of the condenser 15 and the leakage resistance 16 is given such a high value that the condenser 15 is discharged so slowly that the voltage through the condenser cannot follow the rapid decrease of the voltage e_R to the voltage e_{R_1} , which comes after the impulse I_1 , but can follow the slow variation of the amplitudes of the impulses I_1, I_2, I_3 etc. the condenser voltage e_c , i. e. the voltage of the point T relatively to R will have a variation as indicated in Fig. 4. This voltage e_c therefore is varied only in accordance with the slow variation of the impulses I_1, I_2, I_3 etc.

The voltage e_D set up across the diode 17 is the difference between the output voltage e_R of the amplifier 14 and the voltage e_c through the condenser 15. This voltage e_D is represented in Fig. 5 and, as will be clear without further explanation, this voltage varies with the difference between the amplitudes e_{R_1} and e'_{R_1} etc. up to and including e_{R_n} and e'_{R_n} . Consequently, this voltage e_D does not contain any more the component giving rise to shade formations.

From the voltage e_D may be obtained, by means of rectification, a current or voltage the amplitude of which is varied in accordance with the enveloping curve or in accordance with the average curve indicated in dotted line in Fig. 5.

With the usual electron-image scanners, the scanning electron beam is generally suppressed after completion of the scanning of each line or each image. Consequently, the voltage through the resistance 13 is reduced to nought at the end of each line or each image, as shown in Fig. 2. Accordingly, the output voltage of the amplifier 14 takes the most positive value at the end of each line or each image (see Fig. 3) with the result that the condenser is charged to a maximum voltage at the end of each line or each image, as represented in Fig. 4.

When the next line to be scanned begins at a level corresponding to this maximum voltage of the condenser 15, as indicated in Fig. 4, no trouble is experienced. In most cases, however, the starting level of a line will not correspond to the maximum voltage which is the case when components giving rise to shade formations occur already in scanning the first picture points of the line. In this case, the condenser voltage cannot suddenly decrease to the value corresponding to the starting level with the result that during reproduction a new disturbance arises in the image reproduced.

According to the invention, this is obviated by preventing the condenser from being charged further after completion of the scanning of each line or each image. This may be ensured by blocking the rectifier at the same time as the scanning electron beam is suppressed.

In this case, the condenser 15 is discharged between the scanning of two successive lines or images to a voltage e_{C_0} which is lower than the starting level of the next line or the next image as indicated in dotted line in Fig. 4. Since the condenser 15 and the rectifier 17 are so dimensioned that the condenser is rapidly charged when the blockage of the rectifier is eliminated at the beginning of the next line or image, the condenser voltage immediately increases at the beginning of that line up to the value corresponding to the starting level.

Preferably, the diode 17 is substituted for a

rectifier having a control electrode, which electrode is supplied with such a voltage during the time between the scanning of two successive lines or images that this voltage blocks the rectifier in the manner known per se and prevents the condenser 13 from being charged. Preferably, for this purpose the synchronization impulses are supplied to the said electrode.

Another method of removing the component of the voltage through a resistance 13, which gives rise to shade formations, is based on the recognition of the fact that the frequency spectrum of the voltage set up through the resistance 13 comprises two frequency ranges, as indicated in Fig. 6. Firstly, a frequency range S—D consisting of two side bands located symmetrically with respect to the frequency F with which the output currents of the electron-image scanner, due to the presence of the line raster 6, are periodically interrupted and on which the picture currents are modulated, and secondly a frequency range O—A comprising the picture currents and the disturbing component giving rise to shade formation. In case of a really rectangular course of the impulses from which the voltage through the resistance 13 is built up, this voltage comprises further frequency ranges consisting of two side bands of equal width as DC and CD which are located symmetrically with respect to the higher harmonics of the frequency F. These side bands of higher order are not necessary for a proper working and may therefore be suppressed in the amplifier with the method described. In this case, however, the impulses in Figs. 3 and 5 are no longer rectangular, but sinusoidal.

When the line raster 6 has been chosen in the above-mentioned manner the frequency F is double the highest picture current frequency so that the frequency ranges O—A and B—D do not overlap each other.

By conducting, according to the invention, the voltage set up through the resistance 13 across a selective device such, for example as a band-pass filter or a high-pass filter which transmits only frequencies higher than the highest picture current frequency, i. e. the highest frequency required for reproducing a picture with a certain definition, consequently the frequency range B—D, the disturbing component giving rise to shade formation is suppressed. The picture currents transmitted by the filter and modulated on the frequency F may be fed to a rectifier so that after rectification picture currents are obtained.

In most of the known electron-image scanners the picture to be transmitted is projected on the same side of the screen which is also struck by the scanning electron beam. In this case, the line raster 6 is preferably interposed between the two objectives 4 and 7 so that the picture 3 to be transmitted is projected onto the line raster 6 by the objective 4 and the line raster 6 is projected onto the screen 2 by means of the objective 7.

In other electron-image scanners in which a transparent radiation-sensitive screen is utilized and the picture to be transmitted is projected onto the side remote from the device for the production of the scanning beam, the line raster may be directly arranged on the said side of the screen in the electron-image scanner.

When using the line rasters so far described,

5 a portion of the amount of light intended for projection becomes lost. This loss may be avoided by utilizing a lens raster known per se instead of a line raster. One form of construction comprising such a lens raster is represented in Fig. 7. In this construction, a line of the picture to be transmitted is represented by the arrow 18. By means of a lens 19, an image of this line is projected onto the radiation-sensitive screen 20 of an electron-image scanner. Between the lens 19 and the screen 20 is interposed a lens raster 21 constituted by a number of cylindrical lenses mounted next to one another, which number is equal to the number of lines 10 when use is made of a line raster whose axes are perpendicular to the plane of the drawing. An image of the lens 19 is projected onto the screen 20 by each of the cylindrical lenses in such manner that the image of the line 18 projected on the screen 20 is constituted alternately by exposed and unexposed parts of approximately equal width.

What is claimed:

1. In a transmission system for transmitting representations of an optical image, apparatus for correcting for spurious signal and black spot effects comprising photo-sensitive target means onto which said optical image is impressed, electron beam scanning means for scanning said photo-sensitive target means at recurring intervals, means interposed between said photo-sensitive target means and said optical image to interrupt the impression of discrete sections of the image onto said photo-sensitive means, 25 means for sectionally comparing the value of the signals developed from the portions of the target means onto which said image falls with signals developed from the target means from the sections thereof which lack the discrete interrupted sections of the image to be transmitted, said latter means including electrical energy storage means for storing energy representative of the light values on said scanned sections of the target, a leakage path for said electrical energy storage means, rectifying means connected substantially in parallel with said leakage path, means for blocking the scanning action of the target scanning means during one direction of its motion, and means for blocking said rectifying means substantially simultaneously with the blocking of said scanning means.

2. Apparatus in accordance with claim 1, wherein said rectifying means comprises a diode.

3. Apparatus in accordance with claim 1, 30 wherein said rectifying means comprises a thermionic uni-directional conductor having anode, cathode and at least one control electrode, and wherein the impulses for blocking the action of said rectifying means are impressed onto the control electrode-cathode circuit of said thermionic uni-directional conductor.

4. Apparatus in accordance with claim 1, 35 wherein said photo-sensitive target is positioned within a cathode ray tube including means for developing and accelerating an electron beam within the envelope of the tube, and wherein the means for interrupting discrete sections of the optical image impressed onto the photo-sensitive means is positioned within said envelope 40 between the photo-sensitive side of said screen and the optical image.

JAN VAN DER MARK.
